ELECTRIC HEATER

Edward Chase Crowley, Rhinebeck, N. Y.

Application June 13, 1940, Serial No. 340,288

10 Claims.

(Cl. 219—37)

This invention relates to electric heaters and more particularly to electric resistance wire supports and surrounding structures.

The objects of this invention are to provide an improved electric heating unit of the closed type in a three dimensional self supporting frame structure of low thermal mass with hollow bays therein, through which resistance wires pass in protected formation, and with appropriate openings in walls of these bays for the emission of heat from said resistance elements, and in some cases for the passage of drippings therethrough.

Further objects of the invention are to largely confine the conduction of heat to the article or surface desired to be heated; to provide improved electric stove structure; to provide refractory pieces which are readily formed and easily applied; to provide an improved skeleton frame for both forming said bays and for mounting the refractory pieces for the resistance heating element; to provide a skeleton frame structure of rigid characteristics and minimum heat-absorbing mass; to provide a skeleton frame structure which both carries the refractory pieces and constitutes the utensil-supporting grid and is itself supported from below; to enable the skeleton frame to be fabricated in sections; to adapt the structure to utilization of strip metal or flat wire or ribbon for the said frame; to provide a structure which is applicable to oven structure as well as to top-of-the-stove structure; to secure simplicity of construction and operation; and to obtain other advantages and results as may be brought out in the following description.

In the accompanying drawings in which like numerals of reference indicate similar parts throughout the several views:

Figure 1 is a plan of a two burner stove structure embodying my invention with certain parts broken away and one skeleton frame in horizontal section;

Figure 2 is a longitudinal vertical section substantially on line 2—2 of Figure 1;

Figure 3 is a transverse sectional view substantially on line 3—3 of Figure 1;

Figures 4 and 5 are perspective views of skeleton frame sections, which when assembled constitute the skeleton frame;

Figure 6 is a perspective view of one of the refractory pieces;

Figure 7 is a perspective view of a portion of parallel walls of the skeleton frame ready to receive one of the refractory pieces;

Figure 8 is a perspective view of a portion of two of the parallel walls of the frame, similar to Fig. 7, showing a slightly modified construction;

Figure 9 is a perspective view of structural

elements utilized in adapting the invention to use in an oven;

Figure 10 is a sectional plan of a portion of the oven structure assembly;

Figure 11 is a vertical elevation of my invention adapted to be used as a tubular heater; and

Figure 12 is a transverse sectional view of the same, on line 12—12 of Figure 11.

Referring to the specific structure illustrated in Figures 1 to 6 inclusive, where the invention is shown in connection with use as stove top burners, the reference numeral 15 designates in general the stove body here indicated as adapted for two units or burners. The particular stove body here shown comprises a rectangular hollow frame with upright side and end walls and with inturned flanges next the tops thereof for constituting the top surface 16 of the stove body, and with inturned bottom flanges 16' on the side and rear walls for resting upon a supporting surface. The burner units are situated within the open space provided within the confines of the upper inturned flanges and in such manner that the tops of the burner units are substantially in the same plane with said flanges. At one end, which for convenience will be referred to as the back of the stove, the wall there situated is extended upwardly a suitable distance above the stove top 16, in the nature of a splash board, and provides suitable means for supporting current controlling switches 17 in any suitable manner.

Spaced below the stove top 16 in a plane parallel thereto, are a plurality of fixed brackets 18, shown, for instance, in Fig. 3, as flat arches, that is, horizontal cross-reaches with downwardly bent ends having outwardly extending feet resting upon the upper surface of the lower side flanges 16', with asbestos pads 18' interposed between said feet and flanges. The said cross-reaches may be provided with hooked lugs 19 on their undersides and near the ends thereof for support of a heat-reflector 20 hereinafter referred to. The upper sides of said cross-reaches constitute rests or supports for the burner units.

The burner units each preferably are fabricated as skeleton frames, constituting a lattice work, with refractory pieces mounted therein for carrying the electric-resistance heating elements. The skeleton frame is designated generally by numeral 21 and is preferably made up in sections 21', 21'' which interfit and when assembled are secured together to constitute the complete frame. The sections shown separately in Figs. 4 and 5, are fabricated each from strips of metal arranged edgewise and bent in the formation of triangular boxes, forming bays, with a hypotenuse between two opposite corners, and with the two hypotenuse of the two triangular bay forming boxes alined or in continuation one with the other. The said

hypotenuse extend beyond the contiguous corners of the two boxes and join the boxes by a short intervening portion of the extended hypotenuse between said boxes. Another pair of connected triangular boxes, also forming bays, adjoins the first pair with the respective hypotenuse of the first pair contiguous to the hypotenuse of the second pair, thus forming a pair of rectangular boxes with a diagonal 22 across each and with the diagonal of one rectangular box aligned with the diagonal of the other and with the rectangular boxes cornerwise with respect to each other and connected by the extended portions of said hypotenuse which accordingly constitutes an intervening portion 23 of the extended diagonal between the contiguous corners of the rectangular boxes. This connected pair of rectangular boxes, forming its several triangular bays, is herein referred to as a section 21' of the skeleton frame 21, and it will be observed two sections, one shown in Fig. 4 and the complement in Fig. 5 make up the said frame.

The said intervening portion 23 of one section, between and integral with a pair of rectangular boxes, is notched upwardly from its under edge and the other intervening portion of the other section is notched downwardly from its upper edge, thereby enabling the two sections or pairs of rectangular boxes to be interfitted, so as to constitute the symmetrical structure of rectangular skeleton frame, with its plurality of triangular bays of which all the apexes are toward a common center, shown in Figure 1. Thus the diagonals of the several rectangular boxes constitute complete diagonals for the larger rectangle of the skeleton frame. While the foregoing description has been specific to the showing of rectangles and triangles as the geometric shapes involved, the same is done by way of explanation and not necessarily restrictive thereto, since it is within the scope of the invention to employ circular or other configurations for the skeleton frames and correspondingly altered shapes of the components constituting the same.

By use of suitable means 24, such as screws, pins, bolts or the like, and situated for instance in corners of the frame, and projecting upward from the brackets 18, the skeleton frames are centralized with respect to the opening in the stove top, preferably affording a gap or opening 25 next the outer walls of the said frame which are contiguous to the inner edges of the flanges forming the stove top. The gap prevents transmission of heat by conduction from the skeleton frame to the stove body or flanges 16. The skeleton frame is thus isolated from contact with the stove body and any loss of heat by conduction is limited to contact of the skeleton frame with the brackets 18, and in a downward path, and is ultimately interrupted by the interposition of said asbestos pads 18' next the bottom flange of the stove body.

Resting on the top edges of the skeleton frame walls is a plate 26, the upper surface of which is preferably in the same plane as the top surface of the flanges or stove top 16. Said plate constitutes the top wall for the several compartments of a unit. This plate may be, as shown, coextensive with both skeleton frames and spans the distance between those frames in the two-burner stove illustrated. However, said plate, like the skeleton frames, leaves the gap or opening 25 between its periphery and inner edges of the flanges, and thus prevents con-

duction of heat from the plate to the stove body or flanges 16.

Returning now to detailed description of the skeleton frame in its relation to the electric-resistance heating element, it is to be observed that by the construction heretofore described, the diagonals are double walls which are, for the greater part of their lengths, offset to provide a space 27 therebetween. Likewise, the contiguous walls of the assembled rectangles have the greater parts of their lengths offset to provide similar spaces 27 therebetween. Thus, between all adjacent bays the frame provides double or contiguous walls and said walls are, for the greater parts of their lengths between bays, spaced and parallel in each instance.

Two of the contiguous walls of the two sections 21', 21', and portions of aligned walls intercepted thereby, are of less height, as indicated at 28, than the remaining walls and/or portions of walls, so as to provide entry space and fan-like distribution of lead-in wires 29 for the current. The others of the contiguous walls than the ones just mentioned are recessed or notched downwardly from their upper edges, as at 30, with the notches of contiguous walls directly opposite each other. Refractory pieces 31 are provided which will span contiguous walls and substantially fill the notches. Tenons 32 project from the lower mid-portion of these refractory pieces, said tenons having a thickness appropriate to substantially fit between said contiguous walls of the frame, and thus keep the refractory pieces from sliding transverse to the walls out of the notches. Corresponding holes 33 in the tenons and 34 in the walls beneath the notches may be provided if so desired, and in the absence of plate 26 then enable the refractory pieces to be pinned, bolted or otherwise retained in the notches.

As shown, each pair of contiguous walls provides a series of three notches thereby accommodating a series of three refractory pieces for each pair of contiguous walls, and the arrangement of walls being such that they cross or emanate from a common center, the refractory pieces at corresponding distances from that center will be situated on or define points of circles about that center. The several refractory pieces have holes 35 therethrough in directions perpendicular to the respective walls where situated. Obviously a single refractory piece having three holes 35 therein may be used by merging said three notches 30 into one continuous notch. Passed through these holes 35 are electric-resistance heater-elements 36, preferably one for each of the successive circular series of refractory pieces. Each heater element, being passed through the refractory pieces at equal distances from the center, assumes an arcuate shape and by terminating both ends thereof in the vicinity of the part of the skeleton frame having the lower wall, appropriate connection can be made with the lead-in wires situated thereat. Part of each heating element passes through each bay, so no matter which element is heated, each bay is affected.

The electric-resistance heater elements are each shown, by way of illustration, as of helical formation, and are exposed in all directions within the bays to the walls thereof. Each element is likewise an individual heating unit usable alone or in combination with one or more of the other elements. By way of example, the innermost element may be, let us say, 250 watts,

the middle element 500 watts and the outermost element 750 watts. Accordingly, by use of one element alone, or combinations of elements operating simultaneously, a variety of heats may be accomplished by electric consumption of 250 watts, 500 watts, 750 watts, 1000 watts, 1250 watts or 1500 watts. Each heating element is connected individually through a separate one of the switches 17, thereby enabling the user to manually throw the desired one or combination of heating elements into use at will.

The above description makes it apparent that the heating elements are situated within the severals bays between the upper or stove-top plate 26 and the under or reflector plate 20, which accordingly constitute the top and bottom walls of said bays. Both of those plates are preferably of relatively small mass so as to have minimum heat-absorbing capacity. Furthermore, said upper and lower plates are both provided with a plurality of arcuate slots or other openings 37, 38 respectively therein, situated to have corresponding positions one above the other and offset from the heater elements, that is, so that the arcuate slots or openings of the upper plate are directly over the arcuate slots or openings of the lower plate, and with no part of the heater element directly between opposite upper and lower openings. The heater elements are, on the other hand, directly between respective opposed solid portions of the plates and thus protected by those solid portions from drippings which are free to pass directly through the openings. Beneath the lower plate, here shown slidably resting on lower flanges 16' of the stove body, is a drip pan 39, somewhat larger than the said under plate. As the drippings will thus pass through the reflector plate, said plate may be retained clean and brilliant for maintaining maximum efficiency for heat reflection. Suitable means, such as downwardly pressed ribs 40 in the reflector pan engaging the hooked lugs 19, may be provided for positioning the under or reflector plate 20, enabling said plate to be also conveniently removed for cleaning and returned to proper place. The upper or top plate 26 is likewise removable for cleaning purposes and is shown provided with a depending peripheral flange 41 so it may be replaced and retained from lateral dislocation in use. The construction is accordingly such that the stove top may be utilized for visible broiling purposes.

The refractory pieces are preferably restrained from upward removal by the situation of top plate 26 thereover. Said top plate has its upper surface in a plane with the top surface of stove top flanges without any protuberances, and thus cooking utensils may be slid from place to place thereon without having to be lifted or suffering interference. The refractory pieces are made as small as practicable, and are actually smaller than would appear from the drawings, where, to clearly illustrate walls, increase of thicknesses of the showing was necessary. In actual construction, a far greater proportion of heating element of even the inner element is exposed than is covered by or included within the refractory pieces. Furthermore, the holes through the refractory pieces flare at opposite ends so that there is minimum contact of heating element with the refractory pieces and heat will readily emanate from around the heater out of said holes.

In actual manufacture the refractory pieces are

given a dimension lengthwise of the holes for the heating element very slightly larger than the distance from the outside faces of the parallel walls supporting the same. Said pieces are each formed with shoulders next the tenon so as to rest on the corresponding edges of the notches of the walls. However, if desired, and as indicated, in Figure 8, the bottom edge of the notch may be formed by bending of all or part of the metal stamped from the notch into a horizontal or shelf-like position, as at 42. Such structure has the advantage of increasing the rigidity of the wall as well as increasing the area of supporting engagement with the refractory piece.

For purposes of adapting the invention to oven structure, a skeleton frame 43 is illustrated in Figure 9 providing a horizontally disposed bottom frame section 44 substantially coextensive with the bottom area of an oven, and upright frame sections 45, 45, from the sides of the bottom section. These several sections are constructed from strips or ribbons of metal with portions thereof parallel and closely spaced to constitute parallel walls 46 for reception of the aforementioned tenons of the heretofore described refractory pieces. These walls 46 are notched at 47, as before, to receive the refractory pieces in the notches. A heater-element preferably of helical construction as previously described, is passed back and forth on a path as indicated by dot and dash lines 48 to make series connection with a pair of prongs 49, 49 at the rear of the bottom section 44. These prongs will enter suitable sockets (not shown) for completing electric circuit connection when the frame is slid home in the oven, such circuit of course including an appropriate switch (not shown) for manipulation by the user. An appropriate top plate 50 is provided to seat between and face the side frame sections and to seat upon and face the bottom frame section. This top plate has runways 51 for the usual oven grill or shelf. Runners 52 are provided beneath the skeleton frame as part thereof said runners being wide enough to receive bolts, rivets or the like entering both the bottom section and side sections for holding said sections assembled with respect to each other, and the top plate likewise is flanged at front and back and adapted to be held by part of said bolts passing therethrough. The runners extend from front to back next the sides and enable the skeleton frame and plate to be removed as a unit from the oven. The top plate has suitable slots 53 therein offset in disposition from directly overlying the heater element.

The disposition of the heater element in the side frame sections as well as in the bottom section affords quick heating and distribution of heat in the oven. Fabrication of the frames from strips, bent back and forth and, for each section, included within a peripheral enclosing frame piece to which they are welded or otherwise secured, adds to simplicity of construction from a minimum number of parts, obtains unit parts few in number and rigid in character. In both this construction and the stove-top construction previously described, the vertical disposition of the parallel walls affords a rigid support for cooking utensils with employment of lightweight or thin-gauge metal, and this minimizes the mass and conduction characteristics of the skeleton frame. A reflector plate 20' may be provided, as indicated, beneath the bottom skeleton frame section and at the outside of the upright sections. The bottom portion of this reflector plate has openings 38' therein directly

below the openings or slots 53 of the top plate and thus will permit drippings to pass directly through.

As indicated in Figures 11 and 12, the invention is also applicable to use with heater elements for tubular heaters, such as are employed for tank or water heaters. In said figures, a plurality of pairs of parallel closely spaced walls 54 are provided. These pairs of walls are shown longitudinally disposed as a circular grouping so that two of the pairs are diametrically opposite and the other two pairs while also diametrically opposite to each other are in a diametric plane normal to the similar diametric plane of the first pair. The outer edges of all of these walls are notched inward, as at 55, to receive the refractory pieces previously described, and the walls are spaced properly, as before, to receive the tenons of those pieces. The notches are also properly positioned lengthwise of the walls to accommodate a spiral disposition of the heater element 56. Said heater element is again preferably a helical coil of suitable electrical capacity.

The refractory pieces are held in place in the notches by band-like frames or plates 57 extending lengthwise of and normal to the parallel walls and connected in pairs at top and bottom ends of said walls. The structure is therefore one which enables the skeleton frame, with plates 57 applied thereto, to be handled and manipulated as a unit, and inserted as such into the tube 53 forming part of the water heater or similar device. The metal used in each case for the notched refractory-element supporting wall is preferably strip metal generally known in the trade as flat wire or ribbon, and possesses the desired thin-gauge characteristic.

Obviously other detail changes, modifications and uses may be made than those here specifically illustrated and described, without departing from the spirit or scope of the invention, and I do not wish to be understood as limiting myself to the details of disclosure except as set forth in the following claims when construed in the light of the prior art.

I claim:

1. An electric heating unit comprising a skeleton lattice-work frame, insulator elements with transverse bores therein supported in spaced apart relationship in said frame, and an electric heating element disposed throughout said frame and threaded through and supported in said bores in said insulators, said skeleton lattice-work frame being composed of sections of strip material disposed both to constitute said frame and to form in said frame substantially parallel, narrowly spaced-apart, two wall supports for said insulator elements with parallel notched openings in said two walls, and said insulator elements constituting a bridge for said bore between and across both of said two walls and fitting snugly in said notched openings and between said walls.

2. An electric heating unit as set forth in claim 1, wherein said insulator elements are substantially rectangular in shape with a bore extending transversely therethrough and wherein said insulator elements are narrowed in cross section in the lower part thereof to provide two rabbeted shoulders and a projecting tenon so that said rabbeted shoulders must both bear upon

the notched portions of said two wall supports, with said transverse bore extending between and beyond the notches in said two wall supports, with said projecting tenon disposed in snug fit in the space between said two wall supports below said notches.

3. An electric heating unit as set forth in claim 1, wherein said insulator elements and said notched two wall supports have corresponding openings for receiving locking pins for holding the insulator elements in assembled relation with said wall supports.

4. An electric heating unit such as set forth in claim 1, wherein the said unit has an exterior casing, a part of which is formed by part of said skeleton lattice-work frame as herein described.

5. An electric heating unit such as set forth in claim 1, having a heat reflector spaced from said lattice-work to reflect radiant heat to and through said lattice-work as herein described.

6. An electric heater providing a detachable electric heating unit having bare resistance elements, a metal casing in hollow formation in spaced relation to and surrounding and protecting said resistance elements on all sides, ceramic buttons supporting said resistance elements at intervals of the length of said elements, metal strips which form part of said casing and also form an independent three dimensional skeleton metal frame support for said ceramic buttons and resistance elements, said frame holding the ceramic buttons and resistance elements in spaced-apart relationship to each other and to said casing, said unit having for the top and bottom walls of its said casing separately detachable metal plates having aligned openings therein, said resistor elements being offset from alignment of said openings.

7. An electric heater having heating unit as described in claim 6 and having its said top plate together with any objects placed thereon supported by said frame and having its bottom plate constituting a reflector plate horizontally detachable while the unit remains in operation.

8. An electric heater having a heating unit as described in claim 6 disposed in a frame and having supports disposed at the bottom of the unit interposed between said unit and said frame and supporting said unit in a completely isolated position within and completely out of contact with said frame, and heat conduction insulating means interposed between said support and frame, whereby the unit is supported free from heat-conducting physical contact with the said frame.

9. An electric heater in accordance with claim 6 disposed in a frame and wherein said top detachable plate of the heating unit has its upper surface in the same plane as the upper surface of the top wall of the said frame.

10. An electric heater in accordance with claim 6 disposed in a frame and wherein said top detachable plate of the heating unit has its upper surface in the same plane as the upper surface of the top wall of the said frame, and wherein a peripheral gap is provided around said top plate and the said top wall of the said frame for heat-insulating purposes.
